UNITED STATES PATENT OFFICE

JOHN J. BOUCHARD, OF BRADFORD, PENNSYLVANIA

COMBINED PIPE CUTTER AND THREADER

Application filed September 25, 1929. Serial No. 395,129.

This invention relates to the type of tool which is adapted to cut a pipe and thread the end adjacent the cut, thereby obviating the provision and the use of two separate and independent tools for the performance of such work.

The invention contemplates combining with the usual threading die a cutter for severance of a pipe simultaneously with the formation of the threads, the parts being positioned so that when the threads are fully formed the pipe is cut in two.

While the drawing illustrates a preferred embodiment of the invention, it is to be understood that in adapting the means to meet specific needs and requirements, the design may be varied and such other changes in the minor details of the invention claimed, without departing from the spirit thereof.

For a full understanding of the invention and the merits thereof, reference is to be had to the following description and the drawing hereto attached, in which:

Figure 1 is a plan view of a stock of well known construction provided with threading dies fitted with pipe cutters embodying the invention.

Figure 2 is a longitudinal sectional view of the threading dies and applied pipe cutters in operative positions when simultaneously cutting and threading a pipe.

Figure 3 is a detail perspective view of a threading die and pipe cutter the parts being separated.

Figure 4 is a detail sectional view on the line 4—4 of Figure 3.

Figure 5 is a detail sectional view on the line 5—5 of Figure 3.

Corresponding and like parts are referred to in the following description and designated in the several views of the drawing by like reference characters.

The numeral 1 denotes a stock of well known construction adapted to receive a pair of threading dies 2. The dies 2 are held in place by means of screws 3 and are adjusted by means of screws 40. These parts are of well known construction and arrangement and are illustrated to demonstrate the application of the invention which resides in

the pipe cutters and their relation to the threading dies 2.

Each of the dies 2 is provided with a pipe cutter which consists of a plate 4 and points 5 and 6, the point 5 constituting a follower and the point 6 a cutter. The plate 4 usually consists of tempered tool steel and is attached to a side of the threading die and secured by means of screws 7 or other suitable fastening means. The outer face or side of the threading die is recessed adjacent the cutting end to provide a seat 8 for reception of the cutter, thereby relieving the screws 7 of the stress incident to pressure exerted upon the cutter 4 when the tool is in operation. This arrangement also permits of the cutter coming flush with the outer face or side of the threading die. The cutting point 6 is beveled to an edge and sloped to provide clearance. The follower point 5 is beveled on opposite sides. The points 5 and 6 are separated to admit of their proper and independent functioning as will readily be appreciated. When the cutters 4 are properly applied to the threading dies their points 5 and 6 are set slightly in advance of the thread cutting sections of the die 2, as indicated most clearly in Figure 2 of the drawing and as a result the pipe 9 operated upon is completely severed when the threads are fully formed.

When it is required to cut and thread a pipe 9 the screws 3 are loosened and the adjusting screws 40 set to admit of the threading dies 2 being moved apart to permit of the tool being slipped upon the pipe to the required point to be cut. The screws 3 are adapted to retain the threading dies 2 in place and admit of their adjustment by rotating the screws 40. After the tool has been properly positioned upon the pipe 9 the screws 40 are adjusted to advance the threading dies and the pipe cutters to embed the cutters in the pipe after which the tool is oscillated or moved forward and backward approximately a one half turn. The screws 40 are adjusted at intervals, and between each adjustment the tool is oscillated and this operation is repeated until the pipe is completely cut at the required point and the pipe adjacent the cut fully threaded. The

tool is reversely rotated to back it from the pipe and during this operation the thread is made smooth and any burrs removed. It will thus be understood that the pipe is cut and threaded at one operation and by a single tool.

Having thus described the invention, I claim:—

- 5 1. In a pipe cutting and threading tool a threading die having a pipe cutter mounted thereon, the cutting edge of the cutter projecting beyond the thread-forming face.
- 10 2. In a pipe cutting and threading tool a threading die having a pipe cutter mounted thereon and comprising a cutter and a follower, the cutting edge of the cutter projecting beyond the thread-forming face.
- 15 3. A threading die having a portion cut away, and a pipe cutter seated in the cut away portion, and means for holding the pipe cutter in the seat, the cutting edge of the cutter projecting beyond the thread-forming face.
- 20 4. In a pipe cutting and threading tool, a stock, a threading die carried by said stock, and a cutter carried by said die with its cutting edge projecting beyond the thread forming face of the die.
- 25 5. In a pipe cutting and threading tool, a stock, threading dies carried by said stock and having free ends formed with thread cutting faces, one die being adjustable relative to the other, and cutters secured against side faces of said dies with their cutting edges extending beyond the free ends of the dies.
- 30 6. In a pipe cutting and threading tool, a stock, threading dies carried by said stock and having free ends formed with thread cutting faces, one die being adjustable relative to the other, said dies being each reduced in thickness from its free end to form a seat having a shoulder at its inner end, cutting blades fitting upon said seats with their inner ends abutting the shoulders and their outer ends projecting beyond the free ends of the dies and sharpened, and means to removably secure said blades.
